UNITED STATES PATENT OFFICE.

ELLIS HOPWOOD, OF BRADFORD, ENGLAND.

BRUSH FOR CLEARING THE NOIL FROM THE COMB CIRCLES OF COMBING MACHINES.

Application filed July 1, 1925, Serial No. 40,818, and in Great Britain April 27, 1925.

This invention relates to improvements connected with what are known as clearer brushes used in connection with the circles of wool combing machines. The present 5 brushes are circular in shape with annular bristling, and revolve by frictional contact with the comb circle, and to this end are mounted in holders which in turn are mounted on the machine frame, adjustment being 10 provided to allow for decreasing length of bristle.

My invention is in the nature of a brush carrying a shaft adapted to engage a suitable holder which holder is pivoted or tilted 15 able to permit of the removal and replacement of the brush without dismounting the holder, a rest, stay or locating piece for the holder is also provided.

The nature and operation of my invention 20 are fully disclosed in the following specification, and accompanying drawings in which similar reference letters indicate corresponding parts.

Fig. 1 is a side elevation with the brush 25 holder in section.

Fig. 2 is a rear elevation.

Fig. 3 is a plan of the brush holder stay referred to and

Fig. 4 is a plan of the lower bracket which 30 supports the device adjustably from the machine frame.

The brush B is of any usual form adapted to fit a holder H, and to provide ease of removal and insertion of the brush from 35 or into its holder. I provide the brush with a plain central stem or shaft B'. The holder H in the preferred form has a long internal bearing H' leading to a recess H² in which is seated a ball thrust member C 40 pressed towards the brush end by a spring C' which for fitting purposes is retained by a screwed member C² having means to assist in its tightening and removal such as indents C³ Fig. 2. This form of holder has 45 for its purpose obvious advantages in that the brush is readily removable, and after setting in relation to the comb circle (not shewn in the drawings) has a yielding action and will also revolve freely under frictional contact with the comb circle. In order to be able to quickly remove or replace 50 a brush B the holder H is made tilttable, and to this end arms or brackets P on the holder carry a pivot pin P' which passes through a bearing or cross piece D of an adjustable 55 shaft D'.

By merely pivoting the holder, unless a stop or stops was provided the holder could not be retained at its correct angle in relation to the comb circle, therefore it is necessary to provide a suitable stop arrangement which is adjustable, and to this end on the shaft D' I mount a boss F carrying an arm F' which extends towards and under the nose of the holder H as in Fig. 1. If 60 the angle of the holder requires to be altered the arm F' is raised or lowered on the shaft D' and clamped thereto by suitable means such as the screw F² in the boss F. The shaft D' is seater in the boss G' of the 65 base piece G which is bolted in the desired position to a suitable part of the machine frame, substantially in the manner now common to noil brush supports. The base piece G has a boss G' and securing screw G2. 70 By means of the apparatus substantially as before described the brush may be moved nearer to or away from the comb circle. It may be raised and lowered or altered as to angular contact, and when it is desired to remove or replace a brush the holder may be moved upwards in the direction of the arrow 75 in Fig. 1, all without dismounting the apparatus in any way.

The stay arm F' is in no way altered, and to return the brush to its correct position it is only necessary to return the holder against the stay arm F'. 80

It will be found that an apparatus of this 85 description ensures even wear on the bristling of the brush, and such bristling may be used almost to the brush stock.

What I claim is:-

1. A combing-machine brush, comprising 90 a supporting member, a brush holder pivoted to said member for angular movement in a vertical plane, and a brush having a stem mounted for rotation in said holder.

2. A noil brush holder for brushes for 95 clearing noil from the comb circles of combing machines pivotally mounted on a support and provided with a stay arm for ensuring the correct return of the holder.

3. A combing-machine brush, comprising 100 a supporting member, a brush holder pivoted to said member for angular movement in a vertical plane, a brush having a stem mounted for rotation in said holder, and a spring-pressed ball carried by the brush holder engaging the end of said stem and exerting 105 pressure thereon tending to eject the stem from the holder.

110

4. A noil brush holder for brushes for clearing noil from the comb circles of combing machines, pivotally mounted on an adjustable support, said adjustable support carrying and adjustable stay piece or stop for the holder to engage in the working position.

5. A noil brush, a pivoted brush holder, an

adjustable stay and adjustable supporting member for the pivot carried from an adjustable base bracket whereby the brush and its holder may be adjusted as required. ¹⁰

In testimony whereof I have signed my name to this specification.

ELLIS HOPWOOD.
